DIAMOND CUT IN STARFORM

George Saltzman, Arenbergstraat 40,
2000 Anvers, Belgium

Filed Dec. 18, 1974, Ser. No. 533,821

Claims priority, application Belgium July 30, 1974

Term of patent 14 years

Int. Cl. D11—01

U.S. Cl. D11—90

Fig. 1

A

Fig. 2

FIG. 1 is a top plan view of a diamond cut in starform showing my new design;

FIG. 2 is an edge elevational view taken in the direction of arrow A of FIG. 1, the other four edge views being identical.

I claim:

The ornamental design for a diamond cut in starform, as shown and described.
